COMMUTATOR RIVETING MACHINE

Lora E. Poole, Anderson, Ind., assignor to General Motors Corporation, Detroit, Mich., a corporation of Delaware

Application March 24, 1941, Serial No. 384,895

7 Claims. (Cl. 218—1)

This invention relates to the manufacture of commutators for dynamo electric machines and more particularly to commutators comprising an annulus of metal segments separated by pieces of sheet insulation, the segment and insulating pieces having dovetail shanks which are permanently clamped between metal V-rings held together by a hollow core of tubular rivet, the end edges of which are deformed or swaged against the outer edges of the V ring. Such a commutator is shown in Conklin 1,503,484 issued August 5, 1924.

A machine for assembling a commutator of the type disclosed in the Conklin patent is described and claimed in R. W. Baker et al., 1,979,434, granted November 6, 1934. This machine stakes the ends of the tubular rivets sufficiently to retain the commutator parts in assembled relation, but the final riveting operation is not performed by the machine of the Baker patent. The final riveting operation is performed by a separate riveting press which is sufficiently powerful to force the V-rings firmly against the dovetail tangs of the metal segments and insulation pieces, while the ends of the tubular rivet are being upset.

It is an object of the present invention to provide a riveting press equipped with means for applying pressure to the outer or peripheral surfaces of the metal segments, thereby forcing them radially toward the axis of the commutator while at the same time preventing the skewing or twisting of the segments out of planes containing the axis of the commutator. To accomplish this object I provide a movable conveyor, preferably a rotary plate, for carrying a plurality of workholders each adapted to receive a commutator as assembled by the machine of the Baker patent. Each workholder is equipped with means for locating the segments in parallelism with the commutator axis and with radially movable clamping bars for forcing the segments radially toward the commutator axis thereby causing their side surfaces to be brought firmly into engagement with each other. The conveyor brings each commutator clamped in a workholder into alignment with fluid pressure operated riveting devices which cause the V-rings to be forced against the segment tangs, while the ends of the tubular rivet are being upset or swaged against the outer faces of the V-rings. The hydraulic means is caused to advance the riveting devices against the V-rings and tubular rivet automatically in response to location of a commutator in alignment with the riveting means. Following

the riveting operation the riveting devices are automatically retracted and the conveyor resumes its movement to bring another unriveted commutator assembly into position for operation upon it by the riveting device.

A further object of the invention is to provide for a convenient manual control of each workholder to cause its aligning and clamping devices to engage the commutator after the operator places an unriveted commutator within a workholder.

Another object is to provide for automatically releasing the aligning and clamping devices of each workholder as it progresses from the riveting station to the unloading station.

A further object is to provide for automatically ejecting a riveted commutator at the unloading station.

Further objects and advantages of the present invention will be apparent from the following description, reference being had to the accompanying drawings wherein a preferred embodiment of the present invention is clearly shown.

In the drawings:

Fig. 1 is a plan view of a machine embodying the present invention.

Fig. 2 is a fragmentary sectional view on the line 2—2 of Fig. 1.

Fig. 3 is a side view taken in the direction of the arrow 3 of Fig. 1.

Fig. 4 is an end view taken in the direction of the arrow 4 of Fig. 1.

Fig. 5 is a sectional view on line 5—5 of Fig. 1.

Fig. 6 is a side elevation taken in the direction of the arrow 6 of Fig. 1.

Fig. 7 is an end view taken in the direction of the arrow 7 of Fig. 1.

Fig. 8 is a fragmentary side view taken in the direction of the arrow 8 of Fig. 1 showing a portion of the workholder conveyor and the mechanism and causing the aligning for clamping devices of a workholder to be tightened upon the work.

Fig. 9 is a fragmentary view taken in the direction of the arrow 9 of Fig. 8. The part in section is taken on line 9a—9a of Fig. 8.

Fig. 10 is a fragmentary view taken in the direction of the arrow 10 of Fig. 8, and

Fig. 11 is drawn to a larger scale than Fig. 8 shows an end view of one of the workholders disassembled from the conveyor, the part in section at the bottom of Fig. 11 is taken on the line 11a—11a of Fig. 12. The sectional part on the right side of Fig. 11 is taken on the line 11b—11b of Fig. 12.

Fig. 12 is a sectional view on the line 12—12 of Fig. 11.

Fig. 13, which is drawn to a larger scale than Figs. 11 and 12, shows a fragment of the sectional view shown in Fig. 5 of a workholder, a commutator and one of the riveting devices in section and the other in elevation. It will be noted that Fig. 13 shows the workholder in much greater detail than in Fig. 5 in which several details have been omitted owing to the smallness of the scale of Fig. 5.

Fig. 14 is a view on a larger scale than the other views showing the function of the blades 90 and bars 82 in retaining the commutator.

Referring to Figs. 1 to 7, which are drawn to the same scale, a base 20 (Figs. 3, 4, 5, 6) supports a frame 21 providing annular mounting bosses 22 and 23 (Fig. 5) for supporting hydraulic cylinders 24 and 25 respectively for operating the riveting devices to be described. Frame 21 supports brackets 26 and 27 providing bearings 28 and 29, respectively, within which a shaft 30 is journalled. Shaft 30 is connected by keys 31 with a hub 32 attached by screws 33 to a conveyor disc 34 and to a Geneva driven gear 35. Gear 35 (Figs. 4 and 7) is provided with slots 36, each for receiving a roller 37 pivotally mounted on a driving arm 38 fixed to a shaft 39 (Figs. 3, 4, 6 and 7). As shown in Fig. 4 and Geneva gear operating arm 38 has a hub 38a, the contour of which is defined by a concave surface *a*—*c* and a convex surface *a*—*b*—*c*. This portion lies in the plane of the driven gear member 35. The concave surface *a*—*c* provides clearance for the driven member 35 while it is being turned by the roller 37. The convex surface *a*—*b*—*c* is received by similarly shaped concave surfaces of the member 35 in order to lock that member in fixed position while it is not being turned by the roller 37. Shaft 39 carries sprocket 40 connected by a chain 41 with sprocket 42 attached to shaft 43 journalled in bearings provided by a housing 44 mounted on bracket 27. Housing 44 contains a speed reducing gearing including a worm wheel 46 fixed to shaft 43 and a worm 47 fixed to the armature shaft 48 of an electric motor 49 supported by a bracket 49a. Motor 49 drives shaft 39 clockwise as viewed in Fig. 4 in order to move the conveyor disc 34 counterclockwise in Fig. 4. As viewed in Fig. 7 shaft 39 rotates counterclockwise in order to drive disc 34 clockwise. Referring to Figs. 4 and 7 it will be seen that the roller 37 is just entering a slot 36 so that movement of the conveyor disc is about to start. At this instant the high land 51 (Fig. 7) of a cam 50 fixed to shaft 39 has just been moved away from a roller 52 on the upper end of a rod 53 guided by a bracket 54 attached to bracket 27. Upward movement of rod 53 is effected through upward movement of a valve stem 55 which controls a fluid control valve in a housing 56 attached to frame 21. This housing 56 contains a spring which resists downward movement of stem 55 and causes upward movement thereof and of the rod 53 when the high land 51 releases the roller 52. When the valve stem 55 is in the position shown in Fig. 7, the valve within the housing 56 is conditioned so that the riveting devices, to be described later, will be retracted from the work so that the conveyor disc 34 is free to turn.

The conveyor disc 34 carries eight workholders, one of which will now be described with reference to Figs. 6 to 13. Each workholder assembly 60

is received by a counterbored opening 61 provided by conveyor disc 34. The workholder assembly comprises a frame block 62 including a flange 63 provided with radially extending slots 64. Block 62 is provided with radially extending rectangular grooves 65 spaced by triangular shaped bosses 66 having arcuate peripheries 67. The peripheries 67 of all of the bosses 66 collectively provide a bearing for a ring 68 having a gear segment 69 for engaging a gear segment 70 on a lever arm 71 provided with a stud 72 and fixed to a shaft 73 (Fig. 9) journalled in a bearing bracket 74 and restricted in endwise movement by a washer 75 and a screw 76 threaded into the shaft 73. Each bracket 74 has a flange 74a by which screws 74b (Fig. 7) secure the bracket to the conveyor disc 34. Manually controlled means to be described causes the arm 71 to be moved from the full line position at the right hand position of Fig. 8 to the position 71a in dot-dash lines. This causes the ring 68 to be rotated clockwise in Figs. 8 and 11. This causes hard metal rollers 80 carried by the ring 68 to be wedged against camming surfaces 81 provided by radially sliding bars 82 fitted into grooves 65 thereby forcing said bars 82 inwardly so that they engage the metal commutator segments 136a as shown particularly in Fig. 13. When the ring 68 is moved counterclockwise the bars 82 are retracted from the work by the action of springs 83 (Fig. 12) pressing upon pins 84 each connected with a bar 82 and extending into a radial notch 64.

Each bar 82 actuates an aligning blade 90 received in a radial slot 91 in the bar 82 and parallel to the axis of the block 62 and extending from the inner edge of each bar 82 and connecting with a hole 92 passing through the bar 82 in parallel relation to the axis of the block 62. The part of the blade 90 located within the hole 92 carries two cross pins 93 which serve to limit inward movement of the blade 90 radially with respect to the block 62. Each bar 82 provides a radially extending bore 94 which cuts across the hole 92 and intercepts the slot 91. Each bore 94 receives a spring 95 operating to urge the blade 90 outwardly of the bar 82. The workholder illustrated is intended for the reception of a commutator having 28 metal segments 136a (Fig. 14) and spaced by insulating segments 136b. The metal segments 136a are wider radially than the insulating segments 136b; therefore there will be shallow grooves provided by the setback insulating segments between the metal segments. A commutator having 28 metal segments would have 28 shallow grooves. The workholder shown in Figs. 11 and 14 provides seven blades 90; therefore every fourth commutator groove will receive a blade 90 as shown in Fig. 14. In other words, the converging faces of the wedge-shaped end of each blade 90 will be in engagement, respectively, with the adjacent edges of two metal segments 136a; therefore one-half the total number of metal commutator segments 136a are directly engaged by the aligning blades 90. Since every other group of two segments 136a is engaged by a blade 90, all of the metal segments 136a will be located substantially in planes including the commutator axis because the groups of segments which are aligned by the blades 90 cause the other groups of segments to be aligned by the pressure of the groups engaged, the blades 90 acting upon the other groups of metal segments through the in-

sulating segments 136b. The machine attendant places a commutator partially within the opening 100 (Fig. 11) and rotates the commutator so that the seven blades 90 will register with seven grooves at the outer periphery of the commutator. Then the attendant pushes the commutator entirely into the opening 100. As he does this, the seven blades 90 cause the segments 136a adjacent those blades to be located in planes containing the axis of the commutator. Since the segments of the commutator are only loosely assembled with the V-rings and tubular rivet, those metal segments placed in planes containing the axis of the commutator by engagement with the blades 90 cause the other metal segments to be likewise disposed due to pressure exerted upon them by the segments contacting the blades 90, said pressure being transmitted through the intermediate insulating segments. Then by means to be described, the attendant causes the lever 71 to be moved into the position 71a (Fig. 8) to cause the bars 82 and consequently the blades 90 to move inwardly to firmly wedge the commutator segments toward each other while they are being held in planes which include the commutator axis (see Fig. 14).

The bars 82 and ring 68 are retained by an annular plate 96 attached to the block 62 by screws 97. Each block 62 is retained within the disc 34 by the attachment thereto of the flange 14a of bracket 74 which supports the shaft 73 of the gear segment arm 71. The bracket flange 14a overlies the block 62 as well as disc 34 as shown in Figs. 7 and 9 and a portion of the bracket 74 enters a notch 99 in block 62 as shown in Figs. 9 and 11.

The manually controlled mechanism for moving the arm 71 will now be described. Referring to Figs. 4, 8, 9 and 10, to the base 20 is attached a bracket 101 carrying a pivot pin 102 supporting fluid pressure cylinder 103, the flow of fluid to which is controlled by a foot operated valve not shown. The piston rod 104 is connected by clevis 105 and pin 106 with a bell crank lever 107 having a clevis 107a at the end of one of its arms and being pivoted on a stub shaft 108 carried by bracket 109 fixed to frame 21. Lever 107 is connected by link 110 and pin 111 with ears 112 depending from a block 113 slidably guided by rods 114 extending from tubular parts 115 integral with bracket 109. The block 113 carries a screw 116a about which is pivoted a pawl 116 having a lug 117 for engaging the half round stud 72 of lever arm 71 attached to shaft 73. When, due to actuation of the foot operated valve just referred to, air is admitted to the top of cylinder 103, piston rod 104 moves downwardly and block 113 moves to the right and upwardly to cause the lug 117 of lever 116 to engage stud 72 to move the arm 71 from the full line position to the dot dash line position 71a in the righthand part of Fig. 8. This causes the ring 68 to be rotated clockwise in Fig. 8. Ring 68 in turn causes pins 89 (Fig. 11) to be moved clockwise along the outer inclined faces 81 of the bars 82. The pins wedge forwardly the bars 82 thus causing the metal segments of the commutator to be engaged with pressure by the bars 82 and the insulating and metal segments by the aligning and locating blades 90.

The clamped commutator is carried counterclockwise in Figs. 4 and 8 by the conveyor disc 34 to the position in alignment with the riveting devices which will now be described. With ref-

erence to Figs. 5 and 13, the cylinders 24 and 25 are provided respectively with piston rods 124 and 125 attached to sliding rods 126 and 127, respectively, supported in bearings 128 and 129, respectively, provided by frame 21. Movement of the bars 126 and 127 away from the disc 34 is limited by U-washers 130 and 131, respectively. These washers may be removed when it is desired to remove the cylinders 24 and 25, and their associated rods 126 and 127. As the riveting devices carried by the rods 126 and 127 are alike only one of them will be described in detail. For example, the rod 127 (Fig. 13) supports a centrally disposed riveting punch 132 for engaging and riveting over the adjacent edge of a tubular rivet 133 against V-ring 134 forming a part of the commutator assembly 135 which includes an annulus 136 of metal segments 136a and insulating segments 136b (Fig. 14). Insulating V washers 137 are located between the V rings 134 and the annulus 136. While the pressure is being applied by riveting punches 132 to the ends of the tubular sleeve or rivet 133, the two V rings 134 are resiliently forced against the dovetail tangs 25 of the segments 136. This is accomplished by applying pressure through the medium of annular rings 140 integral with circular plates 141 which are slidable on headed studs 142. Pressure is transmitted from the rods 126 and 127 to the plates 141 by a plurality of springs 143 surrounding the studs 142 and housed in pockets 144 provided by rods 126 and 127. After a workholder has first been located in alignment with the aligned riveting devices carried by the rods 126 and 127, the conveyor disc 34 remains stationary for a time. During this time, the roller 52 (Fig. 7) is engaged by the high land 51 of cam 50 in order to cause the valve housed within the valve case 56 to open a passage connecting a source of fluid pressure with the outer ends of the cylinders 24 and 25 thereby causing the rods 126 and 127 to approach the work to effect the riveting operation which has been described. After the riveting operation is performed and before the conveyor disc starts to move again, the high land 51 of cam 50 moves away from the roller 52 to permit the valve in case 56 to disconnect the outer ends of the cylinders 24 and 25 from the source of fluid pressure and to connect the inner ends with said source while venting the outer ends. The riveting devices are thus retracted from the work and the conveyor is again free to move.

As a workholder containing a riveted commutator is moved away from the riveting station toward the next station, that is, toward the ejecting station a cam 150 attached to frame 21 engages the stud 72 and causes the lever 71 to be moved from the dot dash line position 71' to the full line position 71 as shown in the left hand position of Fig. 8. This causes gear segment 70 to rotate clockwise (Fig. 8) and gear 69 to rotate counterclockwise. Pins 80 (Fig. 11) carried by gear 69 rotate about the axis of the commutator to the position shown in Fig. 11 thereby permitting springs 83 (Fig. 12) pushing on pins 84 carried by the bars 82 to retract said bars 82 from engagement with the commutator so that it may be ejected when brought into the ejecting station. During the time in which a commutator is at the riveting station another commutator will be at the ejecting station and in alignment with a plunger 160 (Fig. 2) guided by a tubular part 161 integral with frame 21. This tubular part 161 merges with an annular boss 162 to

which is secured a hydraulic cylinder 163 cooperating with a piston rod 164 attached to rod 160. At the time that pressure fluid is admitted to the outer ends of cylinders 24 and 25 pressure fluid is also admitted to the outer end of cylinder 163 to cause the rod 160 to move toward the right in Fig. 2 in order to eject a commutator assembly 135 from the workholder. At the time pressure fluid is admitted to the inner ends of cylinder 24 and 25, it is admitted also to the inner end of cylinder 163 to cause the rod 160 to be retracted so that the conveyor disc 34 is free to rotate. When a workholder is at the ejecting station shown in Fig. 8 near the central part thereof, its associated clamp operating arm 71 is in the full line position. As this arm moves from the position shown near the middle of Fig. 8 to the position shown at the right position of Fig. 8 the stud 72 thereof engages a beveled camming surface 117a of the lug 117, thereby causing the lever 116 to be cammed downwardly in Fig. 10 against the action of a plunger 170 urged upwardly by a spring 171. After the stud 72 passes to the right of lug 117, and lug 117 will snap upwardly just to the left of the stud 72, thereby locating said lug in position for engagement with the stud 72 when the block 113 is moved upwardly for the purpose of causing the clamp bars of the workholder, then at the loading station, to engage the commutator assembly. Pivotal motion of lever 116 is limited by a screw 172 engaging the ends of a slot 113 provided in said lever.

The machine provides for holding the segments of an annulus of the commutator in planes including the commutator axis while wedging them tightly into closely fitting relation. This operation is performed by the foot controlled pressure cylinder 103 operating through the mechanism which turns the lever 71 counterclockwise (right hand portion of Fig. 8) in order to actuate the commutator clamping bars 82. All other operations of the machine are performed automatically. The motor 49 operates continuously, so long as its control switch (not shown) is closed, to rotate the conveyor disc 34 intermittently. While Geneva gear drive pin 37 is out of engagement with slots 36 of the Geneva driven gear 35, the disc 34 is at rest. During this rest period the commutator in alignment with cylinder 24 (Fig. 4) is riveted, the commutator in alignment with the cylinder 163 is ejected, and the empty workholder above the slide 113 (Fig. 4) is filed with an unriveted commutator by the operator of the machine. During the rest period the high point 51 of cam 50 engages roller 52 to cause a downward movement of valve rod 55 to cause valve 56 to admit pressure fluid to the outer ends of cylinders 24 and 25 to cause the rods 126 and 127 to move to the positions shown in Fig. 13 in order to upset the ends of the rivet 133. Before the rest period ends, the high point 51 of cam 50 moves away from roller 52 to allow a spring (not shown) provided by valve 56 to move valve rod 55 upwardly to condition the valve for admitting pressure fluid to the inner ends of cylinders 24 and 25 so that the rods 126 and 127 will be retracted, thereby retracting the punches 132 and the rings 140 from the riveted commutator and from the carrier disc 34.

While the embodiment of the present invention as herein disclosed, constitutes a preferred form, it is to be understood that other forms might be adopted, all coming within the scope of the claims which follow.

What is claimed is as follows:

1. A machine for riveting the central tubular sleeve or rivet of a commutator assembly including an annulus of metal and insulating segments having dove-tail tangs and including V-rings and a central rivet, said machine comprising a conveyor for supporting a plurality of workholders each adapted to receive a commutator assembly and having means for exerting pressure 5 radially upon the annulus, a manually controlled mechanism interconnected with said means when the workholder is at the loading station and operable to cause said means to become effective, apparatus at the riveting station for riveting the ends of the central rivet against the V-rings, a stationary cam engaged by said means after passing the riveting station for rendering said means non-effective, and a device for ejecting the riveted commutator when located at the delivery station.
2. A machine according to claim 1 having fluid pressure operated riveting apparatus and a fluid pressure operated ejector and having power driven means for effecting intermittent movement 15 of the conveyor and for controlling the advancement of the riveting apparatus and the ejector toward the work and then the retraction thereof while the conveyor is at rest.
3. A machine according to claim 1, in which 20 each work holder is equipped with a rotary cam ring having a gear segment, with a lever having a gear segment engaging the gear segment of the cam ring and with sliding bars movable radially against the commutator annulus, the ring 25 and the bars having cooperating camming provisions whereby rotation of the cam ring by the lever causes the bars to move against the annulus, and in which the lever is rotated to an annulus clamping position by said manually controlled apparatus with which the lever is operatively connected at the loading station, and in 30 which the lever is actuated by the stationary cam to annulus releasing position.
4. A machine according to claim 1 in which 35 the means for exerting radial pressure upon the annulus is equipped with devices for causing the segments of the annulus to be located parallel with the commutator axis.
5. A machine for riveting the central tubular 40 sleeve or rivet of a commutator assembly including an annulus of metal and insulating segments having dove-tail tangs and including V-rings and a central rivet, the outermost edges of the insulating segments being located nearer 45 to the rivet than the outermost edges of the metal segments whereby the outer corner edges of the metal segments are exposed, said machine comprising a workholder providing for the reception of a loosely assembled commutator by 50 axial movement thereof, means provided by the work holder and having surfaces extending parallel to the commutator axis for engaging the exposed corner edges of certain segments as the 55 commutator is inserted within the work holder 55 in order to cause the segments of the commutator to be located in planes containing the axis of the commutator, means provided by the work holder for exerting radial pressure upon the metal segments while they are thus located; and means 60 operable while radial pressure is being exerted upon the metal segments for exerting axial pressure 65 upon the V-rings and for riveting the central rivet against the V-rings.
6. A machine for riveting the central tubular 70 sleeve or rivet of a commutator assembly in-

cluding an annulus of metal and insulating segments having dove-tail tangs and including V-rings and a central rivet, the outermost edges of the insulating segments being located nearer to the rivet than the outermost edges of the metal segments whereby shallow grooves are provided between the metal segments, said machine comprising a work-holder having a cylindrical recess for receiving a loosely assembled commutator inserted axially into the recess, blades located in planes containing the axis of the commutator and each movable edgewise radially of the commutator and providing an edge portion extending a short distance within the recess, said edge portion including surfaces engageable with the corner edges of the metal segments adjacent the groove which receives the blade whereby the insertion of the commutator within the recess

5 causes certain grooves to receive the edges of the blades in consequence whereof the segments are caused to be located in planes containing the axis of the commutator, clamping bars for engaging the outer surfaces of the metal segments and means operable first to cause the blades and then the bars to be forced radially against the metal segments; and means operable while radial pressure is being exerted upon the metal segments for exerting axial pressure upon the V-rings and for riveting the central rivet against the V-rings.

10 15 7. A machine according to claim 6 in which the locating blades are supported by the clamping bars and in which springs are provided for yieldingly transmitting movement to the blades from the bars.

LORA E. POOLE.
